(57) **CLAIM**

The ornamental design for a protective clip for pump-dispensing head, as shown and described.

DESCRIPTION

FIG. 1 is a top perspective view of a protective clip for pump-dispensing head showing the new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof;

FIG. 7 is a bottom plan view thereof.

FIG. 8 is bottom perspective showing the protective clip for pump-dispensing head; and,

FIG. 9 is a perspective view showing the protective clip combined with the pump-dispensing head.

The broken lines in the drawing depict environmental subject matter only and form no part of the claimed design.
